(57) **CLAIM**

The ornamental design for a tower air purifier with scent delivery, as shown and described.

DESCRIPTION

FIG. 1 is a perspective view of a tower air purifier with scent delivery, constructed in accordance with the present invention;

FIG. 2 is a front view thereof;

FIG. 3 is a right side view thereof;

FIG. 4 is a rear view thereof;

FIG. 5 is a bottom view thereof;

FIG. 6 is a left side view thereof; and,

FIG. 7 is a top view thereof.

The broken line showing of parts of the drawings is included for the purpose of illustrating use and environment and forms no part of the claimed design.
